(57) **CLAIM**

I claim the ornamental design for the compass, tear gas expelling device, handle-belt, versatile utility clip and flashlight, as shown and described.

DESCRIPTION

FIG. 1 is a front perspective view of the compass, tear gas

expelling device, handle-belt, versatile utility clip and flashlight embodying by design;

FIG. 2 is a front elevational view of the compass, tear gas expelling device, handle-belt, versatile utility clip and flashlight as shown in FIG. 1;

FIG. 3 is a back elevational view of the compass, tear gas expelling device, handle-belt, versatile utility clip and flashlight as shown in FIG. 1;

FIG. 4 is a left side elevational view of the compass, tear gas expelling device, handle-belt, versatile utility clip and flashlight as shown in FIG. 1;

FIG. 5 is a right side elevational view of the compass, tear gas expelling device, handle-belt, versatile utility clip and flashlight as shown in FIG. 1;

FIG. 6 is a top plan view of the compass, tear gas expelling device, handle-belt, versatile utility clip and flashlight as shown in FIG. 1;

FIG. 7 is a bottom plan view of the compass, tear gas expelling device, handle-belt, versatile utility clip and flashlight as shown in FIG. 1;

FIG. 8 is the compass, tear gas expelling device, handle-belt, versatile utility clip and flashlight in use. The broken lines are shown for illustrative purposes only and from no part of the claimed design; and,

FIG. 9 is the compass, tear gas expelling device, handle-belt, versatile utility clip and flashlight in use. The broken lines are shown for illustrative purpose only and from no part of the claimed design.
